DESIGN FOR A CASING FOR SHAVING IMPLEMENT

Everett Worthington, Scarsdale, N. Y., assignor
to Gillette Safety Razor Company, Boston,
Mass., a corporation of Delaware

Application June 16, 1938, Serial No. 77,887

Term of patent 14 years

To all whom it may concern:

Be it known that I, Everett Worthington, a citizen of the United States, residing at Scarsdale, in the county of Westchester and State of New York, have invented a new, original, and ornamental Design for a Casing for Shaving Implement, of which the following is a specification, reference being had to the accompanying drawing, forming part thereof.

Fig. 1 is an end view of the casing as seen from above;

Fig. 2 is a view in front elevation; and

Fig. 3 is a view in side elevation.

I claim:

The ornamental design for a casing for shaving implements, as shown.

EVERETT WORTHINGTON.
